UNITED STATES PATENT OFFICE.

LOUIS ARNHOLZ, OF WICHITA, KANSAS.

SCHOOL DESK AND CHAIR.

1,370,396.

Specification of Letters Patent.

Patented Mar. 1, 1921.

Application filed September 13, 1920. Serial No. 409,777.

To all whom it may concern:

Be it known that I, LOUIS ARNHOLZ, a citizen of the United States, residing at Wichita, in the county of Sedgwick and 5 State of Kansas, have invented new and useful Improvements in School Desks and Chairs, of which the following is a specification.

My present invention has reference to a 10 school desk and a chair therefor.

My primary object is to produce a desk which is vertically adjustable upon its supporting standard, and a chair therefor which is likewise vertically adjustable upon its 15 supporting standard, the latter being also adjustable longitudinally with respect to the desk, and whereby the desk and chair may be employed by pupils of varying sizes.

It is a further object to produce a vertically 20 adjustable desk and a vertically and longitudinally adjustable chair disposed adjacent to the desk and elevated from the floor on which the device is arranged, the construction being such as to permit the 25 pupil arranging himself on the chair from either of the sides thereof, and the construction being also such as to permit of the device as a unit being swung so that the support for the chair and desk will be arranged 30 vertically to occupy a comparatively small space when not in use and to also permit the proper cleaning of the floor on which the device is arranged.

It is a still further object to produce an 35 article of furniture, of this character, which shall be of a comparatively simple construction, cheaply manufactured, readily adjusted, and thoroughly efficient for the purpose for which it is devised.

With the foregoing and other objects in 40 mind, the improvement resides in the construction, combination and operative arrangement of parts, such as is disclosed by the drawings which accompany and which 45 form part of this specification.

In the drawings:—

Figure 1 is a plan view of an article of furniture constructed in accordance with this invention.

Fig. 2 is a side elevation thereof.

Fig. 3 is a sectional view approximately on the line 3—3 of Fig. 2.

Fig. 4 is a sectional view approximately on the line 4—4 of Fig. 2.

Fig. 5 is a sectional view approximately on the line 5—5 of Fig. 1.

Fig. 6 is a side elevation illustrating the article of furniture swung to position when floor space is required, or when the floor is being cleaned.

Fig. 7 is a perspective view looking toward the under face of the chair bottom.

Fig. 8 is a perspective view of pedestal for the chair.

The base 1 of my improved article of furniture may be of any desired height, length and width, and is channeled longitudinally throughout the length thereof. Preferably but not necessarily, the channeled base 1 has on its sides, adjacent its corners angle 65 brackets 2, the horizontal members of which having openings therethrough and resting on the floor on which the base is arranged, so that securing element may pass through the said openings and rigidly fix the base 70 to the floor. The brackets, even when unattached to the floor provide stabilizing means for the base. The base at one of its ends has secured between the sides thereof an upstanding pedestal 3 which, in the present 75 instance is rectangular and is hollow. On the end of the base provided with the pedestal there is secured one of the leaves of a hinge 4, the lower leaf resting on the floor and being secured thereto. By this arrangement, the article of furniture may be swung 80 (when the brackets are not secured to the floor) to bring the base to a substantially vertical position so that the article of furniture will occupy comparatively small floor 85 space, when such space is needed and also whereby the floor beneath the base may be properly cleaned.

On the sides of the pedestal 3 are wear plates 5 through which centrally extend 90 threaded studs 6.

The desk part of the furniture is of the usual construction, but has its bottom centrally provided with a substantially rectangular opening 7 of a size to freely receive 100 therethrough the pedestal 3. Projecting through the opening and secured to the under face of the top of the desk is a rectangular standard 8. The standard is arranged centrally with respect to the opening and is of a size to be freely received in the hollow pedestal 3.

Depending from the bottom of the desk, in a line with the side walls provided by the opening 7 are centrally slotted plates 9. 110 These plates are designed to receive in the slots thereof the studs 6. The studs are en-

gaged by nuts 10 which bind the slotted plates against the sides of the pedestal 3, and thus retain the desk at vertical adjustments with respect to the pedestal. By having the bore of the pedestal of a rectangular formation and by having the standard 8 of a like formation, a swinging or wobbling movement of the desk on the standard will be prevented. The nuts 10 are preferably winged, so that the same may be easily adjusted on the threaded studs, and consequently the desk may be quickly and easily adjusted on the pedestal and locked at such adjustments.

15 In the channeled base 1, there is arranged for slideable movement the substantially rectangular base portion 11 of a pedestal 12. The base or bottom 11 of the pedestal is provided with binding means 13 that engage with either the bottom or sides of the channeled base 1, whereby the pedestal is retained adjusted longitudinally on the said channeled base. The pedestal 12 is preferably rectangular in cross section and has a similarly shaped bore 14. On the sides of the pedestal are wear plates 15 from which project threaded studs 16.

20 The chair 17 preferably includes a bottom and a back, and on the bottom, at the center thereof there is a depending rectangular standard 18, of a size to be snugly received in the bore 14 of the pedestal 12. To the opposite sides of the standard there are depending slotted plates 19 that are designed to pass over the wear plates on the pedestal and receive in the slots thereof the studs 16. The numeral 20 designates winged nuts which engage with the threaded studs 16 and which contact with the slotted plates 19 to bind the same against the wear plates on the sides of the pedestal. The chair member, it will be noted, may be easily adjusted vertically on its pedestal, and the pedestal may be adjusted longitudinally on the channeled base to bring the chair near or away from the desk to suit the size and convenience of the pupil occupying the chair. The pupil may arrange himself on the channeled

base from either of the sides thereof. The sides of the base are widened at the ends 50 thereof, so that the channel at the part thereof contacted by the feet of the pupil is comparatively shallow, the widened sides stabilizing the pedestal for the chair and the pedestal for the desk.

55 It is thought that the foregoing description, when taken in connection with the drawings, will fully set forth the construction and advantages of the improvement, but it is thought necessary to add that the invention is not to be restricted to the precise structural details set forth in the foregoing description and illustrated by the drawings, as such changes may be made therefrom as fall within the scope of what is 60 claimed.

Having thus described the invention, what I claim, is:—

65 In an article of furniture, a channeled base having one end hingedly connected to a support, laterally projecting elements on the base in a line with the bottom thereof, a hollow pedestal arising from one end of the support, wear plates on the sides thereof having threaded studs, a member having a 70 depending standard received in the pedestal, slotted plates depending from the member receiving the studs, binding elements on the studs contacting the plates for forcing the same against the wear plates and for holding the member adjusted on the pedestal, a second hollow pedestal slideable in the channeled base, means for locking said pedestal on said base, wear plates on the sides of the said pedestal having threaded studs, a 75 member having a depending standard received in the last mentioned pedestal, slotted plates on the last mentioned member receiving the studs of the last mentioned pedestal, and binding elements on the studs for forcing the plates against the wear plates of the pedestal and for sustaining the member vertically adjusted with respect to the pedestal.

80 85 90 95 In testimony whereof I affix my signature.

LOUIS ARNHOLZ.
